LASTING TOOL

Sidney J. Finn, Beverly, Mass., assignor to United
Shoe Machinery Corporation, Paterson, N. J.,
a corporation of New Jersey

Application November 1, 1935, Serial No. 47,844

7 Claims. (Cl. 12—110)

This invention relates to lasting tools, and more particularly to hand pincers for use in pulling uppers over lasts. Such pincers are commonly used to aid in the lasting of shoes or portions thereof in bed-lasting machines, and may be used also to last shoes by hand. An object of the present invention is to provide an improved construction such that the margin of the insole or other shoe bottom part over which the upper is lasted (hereinafter sometimes referred to generically as the sole) will be held close against the bottom of the last opposite the portion of the upper where the pull is applied by the pincers, and also such as to facilitate certain movements of the pincers in pulling the upper.

With the above and other objects in view, the construction herein shown comprises a presser foot arranged to rest on the sole with a portion thereof substantially at the edge of the sole to serve as a hold-down for the margin of the sole, the jaw members of the pincers being movable relatively to this presser foot about a single axis substantially parallel to the bottom of the last to pull the upper heightwise of the last. The jaw members and the presser foot are accordingly so related that the operator can conveniently position the presser foot in the desired close relation to the edge of the sole and then operate the jaws to pull the upper by a simple swinging movement such as he has been accustomed to heretofore in operating hand pincers. Further to facilitate the positioning of the presser foot initially in the correct relation to the sole, the construction shown includes a spring whereby the presser foot is normally held in a position determined by one of the jaws. In accordance with still another feature of the invention the jaw members are connected to the presser foot in a novel manner such as to permit them to be swung also about an axis extending heightwise of the last to pull the upper lengthwise of the edge of the sole without disturbing the presser foot.

The novel features of the invention will now be more particularly described by reference to the accompanying drawing and thereafter pointed out in the claims.

In the drawing,

Fig. 1 is a perspective view illustrating the use of the novel pincers in lasting a shoe in a bed-lasting machine;

Fig. 2 shows a portion of the pincers in elevation, with parts broken away, and further illustrates their relation to the shoe;

Fig. 3 is a plan view of the shoe and of portions of the pincers, with other portions shown

in section substantially on the line III—III of Fig. 2; and

Fig. 4 is a section on the line IV—IV of Fig. 2. The novel pincers comprise a pair of members 2 and 4 pivotally connected together by a pin 6, these members being formed at one end to provide a pair of depending upper-gripping jaws 8 and 10 and at the other end to provide a pair of handles 12 and 14 for closing the jaws on an upper and for operating them to pull the upper. The members 2 and 4 are supported as herein-after described on a presser foot 16 arranged to rest on the insole, in lasting a shoe of the illustrated type, with a portion thereof located substantially at the edge of the insole to serve as a hold-down for the margin of the insole. While pincers constructed in accordance with the invention may be used in lasting different portions of a shoe, they are herein illustrated with reference to their use in lasting the ball portion of a shoe in a bed-lasting machine of the character disclosed in a copending application of J. C. Jorgensen, Serial No. 34,057, filed on July 31, 1935, such a machine including, in addition to the usual toe wipers 18, side wipers 20 which are operated in succession to wipe the marginal portion of the upper inwardly in locations between the toe portion and the shank portion of the shoe. It will be understood that the pincers shown are used to pull the upper in one or more locations adjacent to the edge of each wiper 20 just before the wiper is moved inwardly far enough to wipe the margin of the upper over the insole. It is particularly desirable in operating on this portion of the shoe that pressure be applied to the margin of the insole to insure that it will lie close to the bottom of the last as the wipers are advanced to wipe the upper inwardly, and to control the insole in this manner along a substantial portion of its edge the presser foot 16 is provided with fingers 22 extending therefrom in opposite directions along the edge of the insole. By reference to Fig. 2 it will be seen that the presser foot also engages the insole in another location spaced a considerable distance inwardly over the insole from its edge-hold-down portion.

For connecting the presser foot 16 to the members 2 and 4 there is provided a device or member 24 which is forked at its lower end and is pivotally connected to the presser foot by a pin 26. Extending upwardly from the forked portion of the member 24 is a cylindrical portion 28 swiveled in a socket in the member 2 and reduced in diameter between its ends to receive a plunger 30 whereby the member 2 and the member 24

are held in assembled relation. The plunger 30 is mounted in an opening in the member 2 and is normally held in operative position by a spring 32 which surrounds a diametrically reduced portion of the plunger. This portion of the plunger extends outwardly from the member 2 and has therein a hole 34 in which a pin may be inserted to retract the plunger if it is desired to remove the member 24 from the member 2.

It will be seen that when the parts are assembled as shown the members 2 and 4 are movable relatively to the presser foot 16 about the axis of the pin 26, which extends in substantially parallel relation to the bottom of the last, to pull the upper heightwise of the last, the member 24 partaking of any such movement of the members 2 and 4. If it is desired to pull the margin of the upper more or less also lengthwise of the edge of the insole, as may sometimes be necessary in order to adjust any fullness in the upper along the side of the last, this may be done by swinging the members 2 and 4 about the cylindrical portion 28 of the member 24 without disturbing the position of the presser foot 16, as illustrated by the full and dotted line positions of the jaws in Fig. 3. The plunger 30 bears normally on a flat face 36 (Fig. 4) formed on the cylindrical portion 28 of the member 24 to determine a normal relation between the presser foot and the members 2 and 4 with respect to relative movement about the axis of the cylindrical portion 28. In order to afford further certainty as to the initial position of the presser foot and thus further to facilitate the positioning thereof in the correct relation to the edge of the insole, there is provided a spring 38 mounted at one end in an arm 40 of the member 24 and bearing against the presser foot in a recess 42 provided therein, the spring holding the presser foot normally with its edge-holddown portion against the jaw 8, as indicated by the dotted line position of the jaw in Fig. 2. It will be understood that this comparatively light spring yields as the jaws are swung to pull the upper heightwise of the last, as also illustrated in Fig. 2.

From the foregoing description it will be seen that there is provided a construction in which the presser foot is located initially in a definite relation to the upper-gripping jaws so that the operator can readily position it in exactly the right relation to the edge of the insole, and in the use of which the upper may be pulled heightwise of the last by a simple swinging movement of the jaw members and may be readily pulled also lengthwise of the edge of the insole without disturbing the relation of the presser foot to the margin of the insole. By reference to Fig. 2 of the drawing it will also be seen that the relation between the upper-gripping portions of the jaws and the pin 26 is such that in pulling the upper heightwise of the last the jaws exert no inward pull thereon toward the edge of the insole, but rather tend to pull it in an outward direction.

Having described the invention, what I claim as new and desire to secure by Letters Patent of the United States is:

1. A lasting tool for pulling an upper over a last comprising members connected together for relative swinging movements and provided with a pair of upper-gripping jaws and with a pair of handles for closing said jaws on an upper and for operating them to pull the upper, a presser foot arranged to rest on a sole on the last with a portion thereof substantially at the edge of the

sole to serve as a holddown for the margin of the sole, and means connecting said members to the presser foot for swinging movement relatively to the presser foot about a single axis fixed relatively to the presser foot and substantially parallel to the bottom of the last to pull the upper heightwise of the last, the upper-gripping portions of the jaws being located in such relation to said axis as to pull the upper heightwise of the last without any substantial inward pull thereon toward the edge of the sole. 10

2. A lasting tool for pulling an upper over a last comprising members connected together for relative swinging movements and provided with a pair of upper-gripping jaws and with a pair of handles for closing said jaws on an upper and for operating them to pull the upper, a presser foot arranged to rest on a sole on the last with a portion thereof substantially at the edge of the sole to serve as a holddown for the margin of the sole, a device so mounted in relation to one of said members as to partake of any movement of that member in the pulling of the upper heightwise of the last, and a direct pivotal connection between said device and the presser foot affording provision for swinging movement of both members relatively to the presser foot about an axis substantially parallel to the bottom of the last to pull the upper, the upper-gripping portions of the jaws being located in such relation to said axis as to pull the upper heightwise of the last without any substantial inward pull thereon toward the edge of the sole. 25

3. A lasting tool for pulling an upper over a last comprising members connected together for relative swinging movements and provided with a pair of upper-gripping jaws and with a pair of handles for closing said jaws on an upper and for operating them to pull the upper, a presser foot arranged to rest on a sole on the last with a portion thereof substantially at the edge of the sole to serve as a holddown for the margin of the sole, means connecting said members to the presser foot for swinging movement relatively to the presser foot about a single axis substantially parallel to the bottom of the last to pull the upper heightwise of the last, and a spring arranged to hold the presser foot normally against one of said upper-gripping jaws and against the resistance of which said members are movable relatively to the presser foot to pull the upper. 45

4. A lasting tool for pulling an upper over a last comprising members connected together for relative swinging movements and provided with a pair of upper-gripping jaws and with a pair of handles for closing said jaws on an upper and for operating them to pull the upper, a presser foot arranged to rest on a sole on the last with a portion thereof substantially at the edge of the sole to serve as a holddown for the margin of the sole, and means connecting said members to the presser foot for swinging movement relatively to the presser foot to pull the upper heightwise of the last and also for swinging movement relatively to the presser foot to pull the upper in a direction lengthwise of the edge of the sole. 65

5. A lasting tool for pulling an upper over a last, comprising members connected together for relative swinging movements and provided with a pair of upper-gripping jaws and with a pair of handles for closing said jaws on an upper and for operating them to pull the upper, a presser foot arranged to rest on a sole on the last with a portion thereof substantially at the edge of the

sole to serve as a holdown for the margin of the sole, and a device connecting said members to the presser foot, said device being mounted on the presser foot to swing with the members in a direction to pull the upper heightwise of the last and being movably connected to one of the members to permit the members to swing relatively thereto in a direction to pull the upper lengthwise of the edge of the sole.

6. A lasting tool for pulling an upper over a last, comprising members connected together for relative swinging movements and provided with a pair of upper-gripping jaws and with a pair of handles for closing said jaws on an upper and for operating them to pull the upper, a presser foot arranged to rest on a sole on the last to provide a fulcrum support for said members in pulling the upper heightwise of the last with a portion thereof substantially at the edge of the sole to serve as a holdown for the margin of the sole, a connection between said members and the presser foot constructed to permit the members to swing relatively to the presser foot about an axis extending heightwise of the last to pull the upper lengthwise of the edge of the sole, and spring means for normally maintaining said members and presser foot in a definite relation with respect to relative movement about said axis and against the resistance of which the members are thus movable relatively to the presser foot.

angles to said first-mentioned axis to pull the upper lengthwise of the edge of the sole.

7. A lasting tool for pulling an upper over a last, comprising members connected together for relative swinging movements and provided with a pair of upper-gripping jaws and with a pair of handles for closing said jaws on an upper and for operating them to pull the upper, a presser foot arranged to rest on a sole on the last to provide a fulcrum support for said members in pulling the upper heightwise of the last with a portion thereof substantially at the edge of the sole to serve as a holdown for the margin of the sole, a connection between said members and the presser foot constructed to permit the members to swing relatively to the presser foot about an axis extending heightwise of the last to pull the upper lengthwise of the edge of the sole, and spring means for normally maintaining said members and presser foot in a definite relation with respect to relative movement about said axis and against the resistance of which the members are thus movable relatively to the presser foot.
